CLAIM

The ornamental design for a vehicle front seat, as shown and described.

DESCRIPTION

FIG. 1 is a side view of a vehicle front seat in a first position, according to a first embodiment of the invention, with the opposite side being a mirror image.

FIG. 2 is a front view thereof.

FIG. 3 is a side view of the vehicle front seat in a second position, according to a second embodiment of the invention, with the opposite side being a mirror image.

FIG. 4 is a perspective view thereof.

FIG. 5 is another perspective view thereof.

FIG. 6 is a top view thereof.

FIG. 7 is a rear view thereof.

FIG. 8 is a perspective view of the vehicle front seat in a third position, according to a third embodiment of the invention; and,

FIG. 9 is a perspective view of the vehicle front seat in a fourth position, according to a fourth embodiment of the invention.

The broken lines shown in the figures illustrate portions of the vehicle front seat that form no part of the claimed design.
